US0D1046920S

(12) **United States Design Patent** (10) **Patent No.:** **US D1,046,920 S**
(45) **Date of Patent:** **** Oct. 15, 2024**

(54) **CAM UNIT**

(71) Applicant: **SANKYO OILLESS INDUSTRY, INC.**, Tokyo (JP)

(72) Inventor: **Hiroshi Takahashi**, Tokyo (JP)

(73) Assignee: **SANKYO OILLESS INDUSTRY, INC.**, Tokyo (JP)

(**) Term: **15 Years**

(21) Appl. No.: **29/818,342**

(22) Filed: **Dec. 8, 2021**

(30) **Foreign Application Priority Data**

Jul. 29, 2021 (JP) ..... 2021-016384 D

(51) **LOC (14) Cl.** **15-09**

(57) **CLAIM**

The ornamental design for a cam unit, as shown and described.

DESCRIPTION

FIG. 1 is a bottom view of a cam unit;

FIG. 2 is a front view thereof;

FIG. 3 is a left side view thereof;

FIG. 4 is a rear view thereof;

FIG. 5 is a perspective view thereof;

FIG. 6 is a perspective view thereof;

FIG. 7 is a right side view thereof; and,

FIG. 8 is a top view thereof.

The broken lines depict portions of the cam unit that form no part of the claimed design.

1 Claim, 8 Drawing Sheets
